UNITED STATES PATENT OFFICE.

WYLIE E. HENDERSON, OF LANETT, ALABAMA.

TOP CLEARER FOR ROVING FRAMES.

Application filed December 18, 1926. Serial No. 155,729.

My invention relates to top clearers for roving frames or the like.

An important object of my invention is to dispense with the usual wooden blocks upon which the cots are usually mounted, and which cause considerable trouble by splitting and by wearing the rear side of the cot.

Another object of my invention is the provision of a device of the above mentioned character in which the cots may be reversed or replaced at will.

A further object of my invention is to provide a device of this character in which the whole top clearer does not rest upon the rollers.

Other objects and advantages of my invention will be apparent during the course of the following description.

In the accompanying drawings which form a part of this specification and wherein like characters of reference denote like or corresponding parts throughout the same,

Figure 1 is a bottom plan view of my invention,

Figure 2 is a central transverse section thereof,

Figure 3 is a central longitudinal sectional view therethrough,

Figure 4 is a detail perspective of one of the cot supporting clips, and,

Figure 5 is a detail view of the rod and slot connection.

In the drawings, wherein for the purpose of illustration is shown a preferred embodiment of my invention, the numeral 10 designates the clearer cover which is formed of sheet metal and has its edges bent over to form the front and rear flanges 11. Brackets 12 are arranged adjacent the ends of the

cover 10 and have projections 13 at their ends to make pivotal connection with the spinning or roving frame (not shown). The brackets 12 are provided with vertical slots 14 arranged adjacent the center of the clearer cover which are adapted to support the ends of a longitudinally arranged rod 15

having a reduced extension 16 at one end to engage one of the slots 14 and being substantially oval in cross section. The other end 50 of the rod 15 is provided with a screw or bolt 17 adapted to be removably secured to the end of the rod to removably and slidably secure the rod 15 between the brackets 12.

Clips 18, generally U-shaped in outline and preferably formed from wire, are adapted to

have their free ends inserted in spaced openings 19 in the rod 15 and are arranged diametrically opposite each other on the front and rear sides of the rod 15. The openings 19 on opposite sides of the rod are preferably offset, and may penetrate to the far side of the rod if desired. These openings are shown as being offset vertically, but may be offset laterally if it be so desired.

In assembling, the cots 20 are passed over the clips 18 which are then inserted into the openings in the rod. The outer ends of the clips are bent or offset, as shown, in order to space the cots from the rod 15. It will be seen that the cots will hold the clips in the openings 19, but that they may be removed by applying a little pressure.

With my improved device the cots may be reversed, when worn, or may be easily replaced by removing the clips 18. By reason of the fact that the ends of the clips are bent, the cots are spaced from the rod 15 and will consequently not be subjected to undue wear incident to being pressed thereagainst.

Only the weight of the cots and the rod 15 will rest upon the rollers by reason of the slots 14 and members 16 and 17 which allow of a vertical sliding movement between the rod 15 and clearer cover 10.

While I have shown and described the preferred embodiment of my invention it is to be understood that various changes in the size, shape and arrangement of parts may be resorted to without departing from the spirit of my invention or the scope of the subjoined claims.

Having thus described my invention, what I claim and desire to protect by Letters Patent is:

1. A device of the character described comprising a cover, a longitudinally arranged rod slidably secured thereto, clips secured to said rod, and adapted to support a cot.

2. A device of the character described comprising a cover, a rod arranged thereon and having openings in its sides, clips having their ends arranged in the openings in the sides of the rod, and a cot adapted to be supported by said clips, said cot serving to retain the ends of the clips in the openings in the rod.

3. A device of the character described comprising a cover, a rod longitudinally arranged thereon and having openings therein,

clips having their ends arranged in the openings in the rod and adapted to support a cot, the outer ends of the clips being bent to support the cot in spaced relation to the rod, the 5 clips being held in position in the openings in the rod by the cot.

4. A device of the character described comprising a cover, a rod longitudinally arranged thereon and having openings therein, 10 a roll clearing cot, clips secured to said cot and having their ends inserted in the openings in the rod, the ends of the clips being bent to space the cot from the rod and the major portion of the clips being substantially 15 parallel with the cot.

5. A device of the character described comprising a cover, a rod longitudinally arranged thereon and having openings therein on opposite sides thereof, a roll clearing cot, 20 and substantially U-shaped clips having their ends inserted in the openings in either side of the rod and having their outer ends bent to support the cot in spaced relation to the

rod, the major portion of the clips being arranged in parallel relation with respect to 25 the cot.

6. A device of the character described comprising a cover, a longitudinally extending rod slidably secured thereto and having openings in opposite sides thereof, a roll 30 clearing cot, and substantially U-shaped clips supporting said cot and arranged on either side of the rod, the inner ends of the clips being inserted in the openings in the rod and retained therein by the cot, the outer 35 ends of the clips being bent to space the cot from the rod.

7. A device of the character described comprising a cover, a longitudinally extending rod secured thereon in spaced relation to 40 the sides of the cover, clips secured to said rod and extending laterally therefrom, and a cot adapted to be supported by said clips.

In testimony whereof I affix my signature

WYLIE E. HENDERSON
